UNITED STATES PATENT OFFICE.

THOMAS SHIPLEY, OF YORK, PENNSYLVANIA

AIR-BLOWING FITTING WITH INTERNAL CLEANING-WIRE.

1,331,283.

Specification of Letters Patent. Patented Feb. 17, 1920.

Application filed June 10, 1919. Serial No. 303,224.

To all whom it may concern:

Be it known that I, THOMAS SHIPLEY, a citizen of the United States, and a resident of the city of York, in the county of York and State of Pennsylvania, have invented a certain new and useful Improvement in Air-Blowing Fittings with Internal Cleaning-Wire, of which the following is a specification.

10 My invention relates to apparatus for the manufacture of ice from raw water under what is known as the high pressure air system, in which air at a comparatively high pressure, say from 18 to 20 pounds pressure, 15 after being dehumidified, flows into the water to be frozen through a tube fixed in the can containing the same, continuously throughout the freezing operation.

In apparatus of the kind in question, a 20 definite amount of air at a definite pressure is necessary for the proper agitation of the water in the freezing cans during the freezing operation. Not only, however, is the use of more air than is absolutely necessary 25 for this purpose uneconomical in that the compression of an unnecessary amount of air is a waste of power, but it is positively detrimental in that it is liable, by undue agitation of the water, to cause it to spill over 30 the sides of the can, the loss of which water not only decreases the desired weight of the ice cake but also weakens the surrounding brine.

An orifice to allow the passage only of 35 the amount of air requisite for the proper agitation of the water would, however, be very small, say about 1/64 of an inch in diameter. To drill such a minute passage, would take time and money; and this minute 40 passage, after it was formed, would be very liable to become closed or clogged up by foreign matter such as dirt, scale and the like, thus impairing materially its usefulness for the purpose for which it was designed.

45 It is the object of my invention to provide means which, while adapted to deliver only the predetermined amount of air under pressure requisite for the proper agitation of the water in the can during the freezing 50 operation, shall be free from the objections above named. To this end my invention consists of the devices and combination of devices which will first be described in connection with the accompanying drawings

forming part of this specification, and will 55 then be more particularly pointed out in the claim.

In said drawings—

Figure 1 is a view partly in longitudinal vertical section and partly in elevation of so 60 much of a freezing can, and an air lateral from the main compressed air header (not shown) as is needed for purposes of explanation, together with the connections between said air lateral and the vertical air 65 tube fixed on said can.

Fig. 2 is a cross sectional view illustrative of the manner in which the vertical air tube is seated in a groove on the outside of the 70 can.

L is an air lateral, which in practice is connected to and draws its supply of air from a main air header which usually runs lengthwise of the brine tank in which the freezing cans are assembled; A is a T the 75 vertical tubular limb of which enters the air lateral from below and is secured therein by a screw threaded joint. Each horizontal branch of the T A is provided with a rubber-lined linen or other suitable hose H, to 80 carry the metallic nozzle-like fitting which connects it with the air tube on its appropriate freezing can. As the connections for each branch of the T are the same, only one complete set is shown—that for the right 85 hand branch. Each piece of hose is fitted onto its branch of the T A where it is held by means of external annular corrugations on the end of the branch over which the end 90 of the hose is drawn. The elastic pressure of the hose upon the branch prevents leakage; but, if such elastic force be not sufficient, it can be supplemented by any suitable means which will assure complete stoppage 95 of leakage, as for example a binding of copper wire tightly wound upon the exterior of that portion of the hose which envelops the branch. At the opposite end of the hose is a metallic tubular elbow fitting B which 100 is designed to receive the compressed air and to conduct and discharge it into the air tube T fixed to the freezing can F. The receiving end of this nozzle-like elbow fitting has an annularly corrugated exterior which is fitted into and secured tightly in 105 this end of the hose precisely as in the branch of the T A at its other end. The discharge end of the tubular elbow fitting B

is adapted to be detachably connected with the air tube T on the freezing can by any suitable air tight joint—in the present instance a ground metallic joint, the discharge 5 end of the fitting B being externally tapered and finished to fit tightly and closely into the correspondingly tapered interior of the tube T which receives it. Extending loosely through the bore of the fitting B is a copper 10 or other suitable metallic wire C the ends of which project beyond the ends of the fitting B, and which is longitudinally bent to conform to the curvature of the bore through which it passes. The end of the wire which 15 projects beyond the receiving end of the fitting is bent into ring or hook shape c to form a convenient stop which prevents the wire from dropping down into the bore. The opposite end of the wire projects a sufficient 20 distance beyond the discharge end of the fitting to furnish a convenient handle c' by which the wire may be manipulated. A short length b of the bore at some point in its length—preferably at or near its receiving end as shown,—although still of considerably greater diameter than is necessary for the passage only of that amount of air requisite for the proper agitation of the water, is of somewhat less diameter than the 25 remaining portion b' of the bore, the enlargement of this portion b' permitting the wire when manipulated for cleaning purposes to have, in addition to a longitudinal reciprocating movement, a movement of lateral vibration which materially enhances its efficiency.

The diameter of the cleaning wire C is such, as compared with the diameter of the contracted portion b of the bore of the fitting B, that the annular space between the two will be only sufficient for the passage of the amount of air requisite to produce the proper agitation of the water in the can. In this way the volume of flow of the compressed air to the water in the freezing can, can be exactly regulated and determined.

The air tube T which for the greater portion of its length is seated in an external groove in the side of the can, enters the interior of the can at a point near the bottom of the latter and thence extends down to the said bottom where it discharges in the usual way, the upper cylindrical end of said tube T extending and being held between the side 50 of the can and the heavy metallic reinforcing band G which encircles the upper part

of the can—all as illustrated in my Patent No. 1,158,320 of October 26, 1915.

I am thus enabled to provide a fitting in the shape of an air nozzle in which the hole or orifice for the passage of air may be made of a size to be readily and economically produced, and subsequently to be constricted and reduced in size to a proper opening for the passage only of the amount of air required, the wire having the double function of serving as an efficient agent for this last named purpose and also as a means for keeping clean and clear of obstruction the thus-formed opening, the device as a whole being so constructed and arranged and located that it can conveniently be reached and manipulated, not only every time a can is connected or disconnected, but at any time, whether the apparatus be in operation or not, its services may be called for.

Having described my improvement and the best way now known to me of carrying the same into practical effect, what I claim herein as new and of my own invention and desire to secure by Letters Patent is as follows:

In apparatus of the kind specified for making ice from raw water, the combination substantially as hereinbefore set forth of the following elements, namely; a can for containing the water to be frozen, provided with a duct through which air may be conducted and discharged into the interior of the can at or near its bottom; a nozzle operatively connected to the source of compressed air supply at its inlet end and, at its discharge end, adapted to be detachably connected to the receiving end of the duct on the can; and a wire loosely fitting, and capable of reciprocatory movement in and longitudinally of the bore of the nozzle, and projecting beyond the discharge end of the same to provide a handle by which it can be manipulated for cleaning purposes—the diameter of the bore at the inlet end of the nozzle, relatively to that of the wire which extends through it, being such as to leave between them an annular opening of predetermined size to limit the flow there-through of compressed air to the amount required to produce and maintain the proper agitation of the water in the can during the freezing operation.

In testimony whereof I affix my signature.

THOMAS SHIPLEY.
